UNITED STATES PATENT OFFICE.

JOSEPH G. CHASSÉ, OF SPRINGFIELD, MASSACHUSETTS, ASSIGNOR, BY DIRECT AND MESNE ASSIGNMENTS, TO BENJN. FAGNANT AND MARIE ANNA BELANGER CHASSÉ, OF SAME PLACE.

ELECTRIC LIGHT.

SPECIFICATION forming part of Letters Patent No. 279,224, dated June 12, 1883.

Application filed January 21, 1882. (No model.)

To all whom it may concern:

Be it known that I, JOSEPH G. CHASSÉ, of Springfield, in the county of Hampden and State of Massachusetts, have made new and 5 useful Improvements in Electric Lights and in Electric Lamps, of which the following is a specification.

The object of my invention is to provide a cheap, neat, and easily-regulated electric 10 lamp of that class in which the light is produced within a vacuum-bulb surrounded by a liquid jacket; and it consists in certain novel combinations of devices, which will be herein-after fully described, and pointed out in the 15 claims.

The accompanying drawing is a side elevation of an electric lighting device, illustrating one practical way of carrying out my invention.

20 The letter *e* designates a vacuum-tube having conducting-wires *b' b'* introduced and sealed therein, preferably by passing through india-rubber plugs *d*, so that they may be adjusted. The vacuum may be produced in any 25 convenient manner.

I provide the leading-wires (in a lamp of this construction) with platinum tips within the tube *e*, and the primary illumination is produced by a rapid succession of electric sparks 30 passing between these tips from one to the other. These sparks could not be relied on alone to give light for practical purposes; but when the rays therefrom are subjected to the refractory and mellowing effect of a transparent or translucent liquid medium their illuminating-power is highly augmented and equalized.

The letter *c* indicates an outer or inclosing bulb or case, in the present instance formed 40 with end extensions, *a a'*, of reduced diameter. The leading-wires *b' b'* pass through these extensions, and are sealed in the ends in any convenient manner. One of them preferably passes through a plug, *f*, having a head, *i*, by 45 which it may be inserted or removed to gain access to the interior. The reduced end ex-

tensions very much facilitate the handling of the lamp and afford passage for the leading-wires, which are passed through their ends.

The liquid may be colorless or colored, simple or compound, transparent, translucent, or opalescent, spirituous, or otherwise. The outer case or bulb may also be transparent or otherwise.

In applying my invention to arc-lamps, the 55 double-walled bells or cylinders or globes have suitable passages for the adjustment of the pencils.

An incandescent lamp may be made similar to that shown in the drawing, except the leading-wires will be connected within the vacuum-tube by a carbon filament, a core of platinum, or other conductor which becomes incandescent when an electric current of sufficient 60 strength passes over it.

Having thus described my invention, what I claim, and desire to secure by Letters Patent, is—

1. The combination, with the vacuum-bulb 70 inclosing the electrodes or illuminator, and having the leading-wires extending from the opposite ends thereof, of the outer bulb entirely surrounding said vacuum-bulb, and provided with reduced end extensions through which the leading-wires pass, and in the ends 75 of which said wires are sealed, and the space between the two bulbs being filled with a liquid, substantially as described.

2. The vacuum-bulb *e*, provided with the elastic plugs inserted in its opposite ends, and 80 the leading-wires passing through said plugs, substantially as described, in combination with the outer bulb inclosing said vacuum-bulb, and having the leading-wires passing through its ends, one of said ends being provided with a removable plug through which 85 one of the leading-wires passes.

JOSEPH G. CHASSÉ.
